SONIC TESTER

Norman W. Schubring, Hazel Park, Mich., assignor to General Motors Corporation, Detroit, Mich., a corporation of Delaware

Filed Oct. 16, 1958, Ser. No. 767,723

5 Claims. (Cl. 73—67.2)

The present invention relates to non-destructive testing and, more particularly, to means for sonically inspecting a workpiece for hidden structural defects.

It has been found that similar workpieces have similar natural resonant frequencies at which they will vibrate. Variations in the workpieces produce corresponding variations in the resonant frequencies thereof. If the workpieces are structurally sound, the variations in the resonant frequencies will be within certain prescribed limits. However, if there are defects such as blow holes, etc. present in the workpiece, the variations in the natural resonant frequencies will be outside of the limits. Accordingly, the structural acceptability of a workpiece can be readily determined by measuring the resonant frequency or frequencies thereof.

Normally, workpieces having simple shapes will have only one fundamental resonant frequency. However, if the workpiece has a complex shape, such as an engine crankshaft, it may have several separate and independent natural resonant frequencies at which it will vibrate as a fundamental mode. In the event a defect is present in the workpiece, one or more of these resonant frequencies will be outside certain predetermined limits. One means of determining the natural resonant frequencies is to excite the workpiece by means of a variable sweep frequency oscillator and observe the amplitude of the resultant forced vibrations in the workpiece in the manner disclosed and claimed in copending application Serial No. 739,894, filed June 4, 1958 and assigned to the common assignee.

The foregoing system measures each and every resonant frequency of the workpiece and provides an accurate determination of the structural soundness of the workpiece. However, it has been found that workpieces produced by a common process will be subjected to certain types of defects at certain locations. These defects will be accompanied by changes in only certain of the natural resonant frequencies. Accordingly, it is now proposed to provide a system in which the workpiece will be forced to vibrate across an entire frequency spectrum but only certain critical resonant frequencies will be observed. In the event these frequencies are within acceptable limits, the workpiece will pass inspection and in the event one or more of the resonant frequencies are outside these limits, the piece will be rejected as defective. More particularly, this is accomplished by providing a separate channel for each of the resonant frequencies under consideration. Each channel includes bandpass filtering means that will suppress all signals having frequencies outside of the acceptable limits and passing only signals having frequencies within the acceptable limits. If a resonant frequency occurs within the confines of the band, the signals passed by the channel will have an amplitude greater than some predetermined amount. If all of the channels pass a resonant signal, the workpiece will be indicated as acceptable. However, if one or more channels do not pass a signal resulting from a resonant condition, the workpiece will be rejected.

In actual practice it has been found that the limits on the cut-off frequencies at the ends of the band are very critical, i.e., the variations in the resonant frequencies of defective and acceptable workpieces are very small. In order to obtain a sharp cut-off at both ends of the band, a pair of trigger circuits are provided that are responsive

2

to the frequency of the oscillator or the frequency of the induced vibrations. These trigger circuits are effective to control the conductivity of a gating circuit. When the sweep frequency passes through the opening critical limit,

5 the gating circuit will become conductive and will pass a signal indicative of the induced vibrations. When the sweep frequency passes through the closing critical limit, the gating circuit will become non-conductive. Thus, in the interval between the actuation of the two trigger circuits, i.e., the limits of the band, the gate circuit will be opened to pass a signal indicative of the induced vibrations and will thus become conductive and non-conductive across a very narrow frequency band and will have very sharp cut-off frequencies.

10 15 The FIGURE is a block diagram of a testing apparatus embodying the present invention.

Referring to the drawings in more detail, the invention is embodied in a testing apparatus 10 particularly adapted for sonically inspecting a workpiece 12 for hidden structural defects. The present apparatus 10 will detect excessive variations in either one or both of two resonant frequencies resulting from defects in the workpiece 12. However, if desired, the complexity of the apparatus 10 may be easily expanded to detect corresponding variations 20 25 in any number of resonant frequencies.

In the present instance the workpiece 12 comprises a casting having an intricate shape such as a crankshaft for an internal combustion engine so that it will have several independent resonant frequencies at which it will vibrate 30 as a fundamental mode. In order to induce forced vibrations in the workpiece 12, a driver transducer 14 is placed in intimate engagement with a surface of the workpiece 12. Thus, any mechanical vibrations in the driver 14 will excite the workpiece 12 and force it to vibrate 35 at a corresponding frequency.

The driver transducer 14 is operatively interconnected with the output of a variable frequency sweep oscillator 16. The oscillator 16 may be of any suitable variety wherein the frequency of the oscillations will progressively 40 change across some frequency spectrum. In the present instance, the frequency spectrum is substantially identical to the audio range, i.e., up to approximately 20 kc. and the oscillator 16 will start oscillating at the lower end of the spectrum and gradually increase without any discontinuity to the upper limit or start at the upper limit of the spectrum and gradually decrease without any discontinuity to the lower limit. It may thus be seen that the output of this oscillator 16 will comprise a continuous wave, the frequency of which will progressively increase 45 50 or decrease across the audio spectrum and the transducer driver 14 will excite the workpiece 12 in a similar fashion.

In a sound casting the tolerances for variations in the resonant frequencies will be a very narrow band and the amplitudes of the induced vibrations at resonance will be 55 much higher than during non-resonant conditions. In other words the Q of the mechanical structure is very high. However, increasing the sweep rate will tend to reduce the effective Q and thereby reduce the maximum amplitudes and broaden the band width. This change becomes very marked when the frequency passes through the resonant band in such a short period of time that the casting does not have an adequate period to absorb enough energy to support the larger vibrations. In addition, at the higher sweep rates, the period of time required 60 65 to dissipate the larger quantities of energy absorbed during resonance will be long compared to the period of time required for the sweep frequency to pass beyond the resonant band.

Thus, the extended periods required to absorb and disperse the energy required to support resonant vibrations will have the apparent effect of decreasing the effective Q and increasing the band width. However, these effects

will be of a very minor magnitude until the sweep rate becomes quite high. After this point any further increases in the sweep rate will produce very marked effects on the apparent Q and band width.

Accordingly, in choosing the rate at which the frequency of the oscillator changes, i.e., the sweep rate, the rate should be high enough to reduce the inspection time to within reasonable limits, but low enough to not adversely affect the accuracy of the apparatus due to excessive lowering of the Q and increasing the band width. As a practical matter, it has been found that when testing a crankshaft, a sweep rate that will cover only the required critical portions of the audio spectrum in a few seconds will not unduly reduce the accuracy of the apparatus 10 and will provide a reasonable inspection time.

The vibrations that are induced into the workpiece 12 are sensed by a pickup transducer 18 which is placed in intimate engagement with the casting. This pickup 18 will be effective to produce an electrical signal having an instantaneous amplitude corresponding to the instantaneous amplitude of the vibrations occurring in the workpiece 12. The output of the pickup 18 is interconnected with the input to an amplifier 20 which is adapted to increase the strength of the pickup signal to a more useful level. The output of the amplifier 20 is interconnected with a plurality of parallel channels A and B. The number of these channels A and B corresponds to the number of resonant frequencies which must be observed to determine the acceptability of the workpiece 12. In the present instance only two channels are shown since only two resonant frequencies are to be investigated. However, by duplication any desired number of channels may be employed.

All of the channels A and B are substantially identical and each include bandpass filter means and a flip-flop circuit 28A and 28B. The flip-flop circuit 28A and 28B is responsive to the amplitude of the signal from the pickup 18 and will normally have no output. However, in the event the amplitude of the signal at the input reaches a level corresponding to a resonant vibration, it will trip the flip-flop circuit 28A and/or 28B and cause the channel A and/or B to have an output signal. The bandpass filter means in each channel is tuned to pass frequencies that are within the tolerance limits for the resonant frequencies onto the flip-flop circuits 28A and 28B. All other frequencies are suppressed before they arrive at the flip-flop circuit.

It has been found that the variations between the resonant frequencies of an acceptable casting and a non-acceptable one are very small. Accordingly, the tolerances as to permissible variations in the resonant frequencies are very small and very critical. In order to have adequate resolution to distinguish between an acceptable and non-acceptable resonant condition, the bandpass filter means in each channel must have very sharp cut-off limits and be capable of adjustment down to a very narrow bandpass.

Accordingly, each of the bandpass filter means includes a pair of trigger circuits 30, 32 or 34, 36, a flip-flop circuit 38 or 40 and a gating circuit 42 or 44 respectively. The trigger circuits 30, 32, 34 and 36 are responsive to the frequency of the oscillator 16. The circuits 30 and 34 include resonant circuits tuned to the frequencies of the opening limits of the bands and the circuits 32 and 36 include resonant circuits tuned to the frequencies of the closing limits of the bands. The circuits 30, 32, 34, and 36 each may include rectifying and smoothing means in the output thereof to provide a pulse output adapted to drive one of the flip-flop circuits 38 or 40. Thus, for the case of an increasing frequency sweep, for example, whenever the frequency increases upwardly through a lower limit, the trigger circuit 30 or 34 will cause the flip-flop circuit 38 or 40 to produce an output signal and whenever the frequency increases upwardly through an upper limit, the trigger circuits 32 or 36 will cause the flip-flop

circuits 38 or 40 to no longer produce an output signal. The signals from the flip-flop circuits 38 and 40 will be effective to cause the gate circuits 42 or 44 to become conductive only during the period when the sweep frequency is between the upper and lower limits of the band of acceptability. As a result, the flip-flop circuits 38 or 40 will respond only to signals in that frequency range.

In the event a resonant condition occurs within the desired frequency range, a signal of increased amplitude 10 will be fed to the flip-flop circuit 28A or 28B and cause an output signal to be fed into a coincidence gate 46. If all of the channels A and B supply such a signal to the coincidence gate 46, it will energize relay 48. This will actuate suitable means to cause the workpiece to be accepted. If a signal is not received from each channel A and B, the relay 48 will cause the workpiece to be rejected.

In order to employ the present apparatus 10 for testing a workpiece 12 for structural defects, the workpiece 12 20 is placed on suitable supports for permitting vibrations therein. The driver transducer 14 and pickup transducer 18 are then connected to the workpiece 12. The switch 50 is then manually closed for a short period to return the frequency of the oscillator 16 to its lower limit and to 25 cause the flip-flop circuits 28A and 28B to be shut off so no signals will be fed to the coincident gate circuit 46. Flip-flop circuits 38 and 40 will also be returned to neutral. The switch 52 is then closed to start the oscillator 16 sweeping the spectrum.

As the sweep commences the pickup 18 will produce a signal that will be fed to the inputs of gates 42 and 44 in each channel A and B. However, the gates 42 and 44 will not permit the signal to pass therethrough. When the sweep frequency reaches frequency f_1 , the trigger circuit 30 will trip the flip-flop circuit 38 and thus open the gate 42, thereby permitting the flip-flop circuit 28A to receive a signal from the pickup 18. When the sweep frequency reaches f_2 , the trigger circuit 32 again trips the flip-flop circuit 38. This will close the gate 42 and prevent a signal reaching the flip-flop circuit 28A. In the event the workpiece 12 is of acceptable quality, a resonant vibration will have occurred when the gate 42 was open and the flip-flop circuit 28A will have received a signal of adequate amplitude to cause it to pass a signal to the coincident gate 46. In the event the workpiece 12 is unacceptable, a resonant vibration may or may not have occurred within the tolerance limits depending on the nature of the defect. Accordingly, the flip-flop circuit may or may not have produced an output signal.

As the sweep frequency continues to change, it will reach frequency f_3 and will cause the trigger circuit 34 to trip the flip-flop circuit 40 and thereby open the gate 44. Thus the signal from the pickup 18 will reach the flip-flop circuit 28B. As the frequency continues its sweep, it will 55 reach frequency f_4 . When this occurs the trigger circuit 36 will trip the flip-flop circuit 40 and close the gate 44, thereby preventing the flip-flop circuit 28B receiving any further signals. If the workpiece 12 is of acceptable quality, a second resonant condition will have occurred 60 between frequencies f_3 and f_4 and the flip-flop circuit 28B will have supplied a second signal to the coincident gate 46. As a result, the coincident gate 46 will have energized the relay 48 and caused the acceptance of the workpiece 12. If the piece is defective, a resonant condition may or may not have occurred between frequencies 65 f_3 and f_4 depending on the nature of the defect.

However, if there is a defect, one or both of the flip-flop circuits 28A or 28B would not have received a larger signal during the bandpass frequencies. Since both circuits 28A and 28B are not feeding signals to the coincidence gate 46, the relay 48 will cause the workpiece to be rejected as being defective.

It is to be understood that, although the invention has been described with specific reference to a particular embodiment thereof, it is not to be so limited since changes

and alterations therein may be made which are within the full intended scope of this invention as defined by the appended claims.

What is claimed is:

1. In a device for detecting flaws in a workpiece, the combination of a variable frequency oscillator, a driver operatively interconnected with said oscillator and adapted to induce variable frequency mechanical vibrations in said workpiece, a vibration pickup responsive to the amplitude of the vibrations induced in said workpiece, a plurality of channels operatively interconnected with said vibration pickup and including bandpass filter means, each of said channels being effective to produce an output signal whenever the amplitudes of said vibrations are in excess of some predetermined amount and the frequency thereof is within the limits of the band for said channel, a coincidence circuit interconnected with said channels and effective to produce an output signal only when each of said channels produces an output signal.

2. In a device for detecting flaws in a workpiece, the combination of a variable frequency oscillator, a driver operatively interconnected with said oscillator and adapted to induce variable frequency mechanical vibrations in said workpiece, a vibration pickup responsive to the amplitude of the vibrations induced in said workpiece, a plurality of separate channels interconnected with said vibration pickup, each of said channels including means responsive to the frequency of said vibrations and adapted to produce an output signal if the amplitudes of the induced vibrations are greater than some predetermined amount when the frequency of said vibration is between some predetermined upper and lower limits, a coincident circuit interconnected with all of said channels and effective to produce an output signal only when each of said channels produces an output signal.

3. In a device for detecting flaws in a workpiece, the combination of a sweep frequency oscillator, a driver operatively interconnected with said oscillator and adapted to induce variable frequency mechanical vibrations in said workpiece, a vibration pickup responsive to the amplitude of the vibrations induced in said workpiece, gating means interconnected with said vibration pickup, trigger circuit means interconnected with said gating means and responsive to the frequency of said oscillations, said trigger circuit means being effective to cause said gating means to become conductive whenever the frequencies of said vibrations are within certain limits.

4. In a device for detecting flaws in a workpiece, the

combination of a sweep frequency oscillator, a driver operatively interconnected with said oscillator and adapted to induce variable frequency vibrations in said workpiece, a vibration pickup responsive to the amplitude of the vibrations induced in said workpiece, a plurality of channels operatively interconnected with said pickup, each of said channels including a gating circuit and a pair of trigger circuits, each of said trigger circuits being responsive to the frequency of said vibrations whereby each pair of trigger circuits will be effective to cause their associated gating circuits to become conductive whenever the frequencies of said vibrations are within certain limits, each of said gating circuits being effective to cause its channel to produce an output signal whenever the gating circuit is conductive and the amplitudes of said vibrations are greater than some predetermined amount.

5. In a device for detecting flaws in a workpiece, the combination of a sweep frequency oscillator, a driver operatively interconnected with said oscillator and adapted to induce variable frequency vibrations in said workpiece, a vibration pickup responsive to the amplitude of the vibrations induced in said workpiece, a plurality of channels operatively interconnected with said pickup, each of said channels including a gating circuit and a pair of trigger circuits, each of said trigger circuits being responsive to the frequency of said vibrations whereby each pair of trigger circuits will be effective to cause their associated gating circuits to become conductive whenever the frequencies of said vibrations are within certain limits, the gating circuits in each of said channels being effective to cause its channel to produce an output signal whenever the amplitudes of said vibrations are greater than a predetermined amount when said gating circuit is conducting, a coincidence circuit operatively interconnected with each of said channels and effective to produce an output signal whenever all of said channels produce an output signal.
